ATTACHMENT FOR MACHINE GUNS

Lewie W. McPherson, Carrollton, Ga.

Application July 26, 1932. Serial No. 624,794

1 Claim. (Cl. 240—2)

This invention relates to attachments for machine guns or other types of automatic firearms and has for the primary object, the provision of a device especially adapted for training persons in the art of firing weapons of the above stated character without the use of ammunition.

Another object of this invention is the provision of a light projecting device adjustably mounted on an automatic gun and automatically operated by the actuation of the firing means of the gun to project light rays covering a given area on a target to indicate clearly to the gunner or observer the accuracy of the aim taken by the gunner.

With these and other objects in view, this invention consists in certain novel features of construction, combination and arrangement of parts to be hereinafter more fully described and claimed.

For a complete understanding of my invention, reference is to be had to the following description and accompanying drawings, in which

Figure 1 is a side elevation illustrating an automatic or machine gun with an attachment applied thereto and constructed in accordance with my invention.

Figure 2 is a fragmentary top plan view illustrating the same.

Figure 3 is a fragmentary end elevation illustrating the attachment associated with the muzzle of the gun.

Figure 4 is a sectional view illustrating the attachment.

Figure 5 is an end elevation partly in section illustrating the attachment removed from the gun.

Figure 6 is a sectional view taken on the line 6—6 of Figure 4.

Figure 7 is a fragmentary plan view illustrating the attachment.

Referring in detail to the drawings, the numeral 1 indicates a conventional type of machine gun to which an attachment 2 is applied and the latter consists of a cylindrical housing 3 having one end closed by a slidably mounted illuminating means 4 and the opposite end closed by a partition 5 provided with an opening 6 to receive a portion of a light projecting means 7. The housing 3 is supported parallel and to one side of the barrel of the gun by brackets 8 and 9. The bracket 8 consists of a circular band 10 mounted on the housing 3 at one end of the latter and carries spaced arms 11 formed integrally with an adjustable band 12 adapted to encircle a cooling jacket 55 for the barrel of the gun as shown in Figure 2.

The bracket 9 consists of an ear 13 suitably secured to the housing 3 to which is detachably and adjustably secured a plate 14 having a slot 15 through which extends the muzzle or barrel of the gun 1. The muzzle or barrel of the gun is equipped with a muzzle gland engaging the walls of the slot 15 whereby the housing 3 may be adjusted relative to the gun for the purpose of zeroing the attachment to the gun.

A cylindrical sleeve or hood 16 is carried by the end of the housing 3 having the partition 5 and is provided with a partition 17 having an opening 18 receiving a portion of the light projecting means 7. The means 7 constitute one section of a field glass provided with the usual apertured ears 19 to connect said section to its companion section. The ears 19 receive a bolt 20 extending through the partitions 5 and 17 where the means 7 is suitably mounted in the hood 16 and the housing 3. The eye piece 21 of the section of the field glass is arranged in alignment with an electric lamp 22 constituting a portion of the illuminating means 14. The electric lamp is mounted in a socket 23 carried by a tubular shield 24 having one end closed as shown at 25. The shield 24 is adjustable lengthwise within the housing 3 to vary the distance between the electric lamp 22 and the light projecting means 7. The socket 23 is electrically connected to a normally opened switch 26 mounted on the firing means of the gun 1. The electrical connection between the switch 26 and the socket 23 is provided with a plug socket 27 to receive a conventional type of electrical out-put plug whereby the lamp 22 and the switch are electrified. When the firing means of the gun is actuated, the electric lamp 22 is illuminated so that the light rays from the lamp will be projected by the means 7 onto a target indicating on the target the accuracy of the aim made by the gunner. The light on the target will remain as long as the trigger or firing means of the gun is held in an operative position, giving the gunner or the observer time to determine the accuracy with which the gun is aimed. A device of this character will permit efficient training of persons in the art of aiming or using firearms of this character without the employment of ammunition thereby rendering a large saving of ammunition and the cost thereof and further permitting the training of persons with a maximum amount of safety.

While I have shown and described the preferred embodiment of my invention, it will be understood that minor changes in construction, combination and arrangement of parts may be

made without departing from the spirit and scope of my invention, as claimed.

Having thus described my invention, what I claim is:—

5 A light attachment for an automatic gun having a cooling jacket surrounding the barrel of said gun comprising a tubular housing, a bracket securing the housing to the cooling jacket of the gun, a second bracket carried by the housing

and having a slot to receive the muzzle of the gun for adjusting the housing relative to the barrel of the gun, an electric light mounted in the housing, light projecting means in said housing, and a switch actuated by the firing medium of the gun and electrically connected to the light and to an electrical source.

Swu

LEWIE W. McPHERSON.
